FOLDABLE LADDER

James Hector Hardie, Montreal, Quebec, Canada,
assignor to The Robert Mitchell Company Limited, Montreal, Quebec, Canada

Application November 18, 1948, Serial No. 60,723

4 Claims. (Cl. 228—36)

1

This invention relates to improvements in foldable ladders equipped with support-engaging hooks projecting above the upper end of the ladder and adapted to be engaged with a support to hold the ladder in either a vertical or an inclined position with reference to the support and the ground or floor surface. Ladders of this type are used in railway sleeping cars for the convenience of the occupants of upper berths; in stores for the convenience of clerks in reaching high shelves for the removal or placement of merchandise; and in various other relations.

The object of the present invention is to provide a generally improved ladder of the type referred to embodying hook operating means for automatically turning the support-engaging hooks to a folded position during the folding of the ladder and to an unfolded position during the unfolding of the ladder.

Other objects, advantages and characteristic features of the invention will be more readily apparent from the following detailed description taken in connection with the accompanying drawings, in which—

Fig. 1 is a front view of a ladder embodying the invention.

Fig. 2 is a side view of the ladder as it appears in its unfolded condition.

Fig. 3 is a fragmentary side view showing the manner in which the component parts of the ladder assembly are folded to an inoperative position.

Fig. 4 is a sectional view taken substantially along the line 4—4 of Fig. 2.

Fig. 5 is a view similar to Fig. 4, but showing the top step of the ladder in its folded position as compared with the unfolded position shown in Fig. 4.

Fig. 6 is a sectional view taken substantially along the section line 6—6 of Fig. 4.

Fig. 7 is a sectional view taken substantially along the section line 7—7 of Fig. 5.

Fig. 8 is a fragmentary side elevational view of the lower portion of one of the hook members.

Fig. 9 is a sectional view taken substantially along the section line 9—9 of Fig. 8.

As shown in these drawings, my improved ladder comprises a series of vertically spaced steps 5 having their forward portions fitted between and pivotally secured to laterally spaced front uprights 6 and having their rear portions fitted between and pivotally secured to laterally spaced rear uprights 7, the pivotal connections between the steps and the uprights being indi-

cated at 8 and being of any suitable construction. The ladder also includes an additional top step or platform 9 having its forward portion fitted between and pivotally secured to the front uprights 6 as hereinafter described. When the ladder is in the unfolded position shown in Figs. 1 and 2 the top step or platform 9 is supported in a horizontal position by means of a supporting rod 10 mounted in brackets 11 carried by the upper portions of the rear uprights 7. The rod 10 merely serves as a support for the top step or platform 9 and is not attached thereto.

The pivotal connection between the front uprights 6 and the top step or platform 9 is shown to advantage in Figs. 4 to 7 inclusive. As here shown each pivotal connection comprises a tubular bearing member 12 extending inwardly from one of the uprights 6 through an opening 13 provided in the adjacent side wall 14 of the top step or platform 9. A bar 15, secured to a rear wall 16 of the step or platform 9, is provided with cylindrical terminal extensions 17 constituting pivots which are rotatably received in the tubular bearings 12 of the uprights 6 to provide pivotal connections about which the top step or platform 9 is swingable from the horizontal position shown in Figs. 2 and 4 to the vertical position shown in Figs. 3 and 5.

Hook members, generally indicated at 19, are slidably and rotatably mounted in the upper portions of the front uprights 6 which, as shown in Figs. 4 and 5, are of hollow tubular construction. Each hook member 19 comprises a bill portion 20 and a shank portion 21.

The shank portion 21 of each hook 19 extends downwardly through a cap 22 closing the upper end of one of the uprights 6 and through an annular spacer member 23 fitted in the upper end of the upright in contact with the top portion 40 of the cap 22, the cap and spacer being secured in place by screws 24 as shown in Fig. 7. The lower end of the shank 21 of each hook 19 is fitted in the upper portion of a tubular guide member 25 and is rigidly secured to said guide member by a fastening pin 26. The guide member 25 is slidably and rotatably fitted in the uprights 6 and is provided, below the lower end of the hook shank 21, with a drilled opening 27 flanked by two communicating recesses 28 and 29 disposed at right angles to each other. The recess 28 and part of the opening 27 are formed by forcing a drill through the wall of the tubular guide member 25 as indicated by dotted lines A in Fig. 9. The recess 28 and the remaining portion of the opening 27 are then formed by drilling

through the wall of the guide 25 in a direction at right angles to the first drilling operation as indicated by dotted lines A' in Fig. 9. A pair of pin-carrying blocks 31 are arranged within the top step or platform 9 adjacent the side walls 14 and are provided, at their outer ends, withoutwardly directed hook operating pins 32. These pins 32 extend outwardly through openings in the side walls 14 of the step or platform 9 and into the tubular guide members 25 through the openings 27 provided in said guide members.

When the ladder is in its unfolded operative condition the component parts thereof are arranged as shown in Figs. 1, 2, 4 and 6, the front uprights 6 being spaced from the rear uprights 7 by the steps 5 and 9 which are disposed in the horizontal position shown in Fig. 2 and the hooks 19 being arranged with their hook bills 20 directed rearwardly and overlying the top step or platform 9. In this condition of the ladder the hooks 19 are in their lowermost position and the hook operating pins 32 of the top step or platform 9 are disposed in the recesses 28 of the tubular guide members 25 attached to the shank portions 21 of the hooks. In this condition of the ladder the hook bills are disposed to be engaged over a support such as the side rail or other support running along the side of an upper berth or bunk. If the hooks 19 are engaged over a support to position the ladder so that it inclines downwardly and outwardly from said support the engagement of the lower ends of the uprights 6 and 7 with the floor surface will cause the rear uprights 7 to be displaced upwardly with reference to the front uprights 6 and, in this case, the pivotal connections between the uprights and the steps 5 and 9 will permit the ladder to take up a horizontal position with reference to the floor line.

When the ladder is not required it is folded to a compact condition by shifting the rear uprights 7 upwardly and inwardly to a folded position against the front uprights 6 as shown to advantage in Fig. 3. During this shifting of the rear uprights 7 the rear portions of the steps 5 and 9 swing upwardly in an anti-clockwise direction about their pivotal connections to the front uprights 6.

When the top step or platform 9 is swung upwardly, either by hand or by the pushing action of the rod 10, from the horizontal position shown in Figs. 1, 2, and 4 to the vertical position shown in Figs. 3 and 5 the hook operating pins 32 carried by the step or platform 9 travel upwardly and forwardly in arcuate slots 34 provided in the uprights 6. The slots 34 are curved about a center coinciding with the center of the pivotal axis afforded by the bearings 12 and the pivots 17 and are positioned as shown in Figs. 6 and 7. As the hook operating pins 32 travel upwardly and forwardly in the slots 34 they act against the top and rear wall portions of the openings 27 of the hook guides 25 to move said guides upwardly in the uprights 6 and to simultaneously cause the guides to rotate in the direction indicated by the arrows in Figs. 4 and 5. This rotation of the guides 25 causes the attached hooks 19 to rotate relatively to the uprights 6 so that the hook bills 20 are turned from the operative position shown in Figs. 1, 2 and 6 to the folded position shown in Figs. 3 and 7. In their last mentioned position the hook bills 20 are directed inward toward each other and lie parallel with the uprights 6. When the ladder is again unfolded to the operative position shown in Figs. 1 and 2 the hook operating pins 32 of the top step or platform 9 travel

downwardly and rearwardly in the arcuate slots 34 as the step or platform 9 is swung downwardly and rearwardly from the position shown in Figs. 3 and 5 to the position shown in Figs. 1, 2 and 4. During this downward and rearward movement thereof the hook operating pins 32 act against the rear and bottom portions of the openings 27 of the tubular hook guides 25 and causes said guides to move downwardly in the uprights 6 and to simultaneously revolve relatively to the uprights in a direction opposite that indicated by the arrows in Figs. 4 and 5. This causes the hook attached to the guides 25 to revolve so that the hook bills 20 are returned to the operative position shown in Figs. 1, 2 and 6.

Having thus described the nature of my invention and a preferred embodiment thereof, it will be understood that various modifications may be resorted to within the scope and spirit of the invention as defined by the appended claims.

I claim:

1. A foldable ladder comprising front and rear pairs of laterally spaced uprights, a vertical series of steps having their forward portions pivotally secured to the uprights of the front pair and their rear portions pivotally secured to the uprights of the rear pair, said ladder being foldable by swinging the steps and one pair of uprights upwardly and inwardly about the pivotal connections between the steps and the other pair of uprights, a pair of hooks rotatably carried by certain of said uprights and hook operating means functioning automatically to turn the hooks to a folded position in response to the folding of the ladder and to an unfolded position in response to the unfolding of the ladder, said hook operating means interlocking the hooks with a part of the ladder which moves relatively to the hook carrying apparatus during folding and unfolding of the ladder.

2. A ladder comprising a front pair of laterally spaced uprights, a rear pair of laterally spaced uprights, a plurality of steps having their forward portions pivotally secured to the front uprights and their rear portions pivotally secured to the rear uprights, an additional step arranged above the first mentioned steps and having its forward portion pivotally secured to the front uprights, said ladder being foldable by shifting the rear uprights and the first mentioned steps upwardly and inwardly about the pivotal connections between said first mentioned steps and the front uprights and being unfoldable by reverse shifting of said rear uprights and said first mentioned steps about the said pivotal connections between the first mentioned steps and the front uprights, supporting means carried by the rear uprights for supporting the rear portion of said additional step in the unfolded condition of the ladder, a separate hook rotatably associated with the upper portion of each front upright and hook operating means interconnecting said hooks and said additional step and operable to automatically turn the hooks to a folded position in response to folding movement of said additional step and to an unfolded position in response to unfolding movement of said additional step.

3. A ladder comprising a front pair of laterally spaced tubular uprights, a rear pair of laterally spaced uprights, a plurality of steps having their forward portions pivotally secured to the front uprights and their rear portions pivotally secured to the rear uprights, an additional step arranged above the first mentioned steps and having its

forward portion pivotally secured to the front uprights, said ladder being foldable by shifting the rear uprights and the steps upwardly and inwardly about the pivotal connections between the steps and the front uprights and being unfoldable by shifting the rear uprights and the steps in the reverse direction about said pivotal connections, means carried by the rear uprights for supporting said additional step in the unfolded condition of the ladder, a separate hook associated with each of the front uprights, each hook having the lower portion of its shank slidably and rotatably fitted in the upper portion of the associated front upright, and hook operating means interconnecting said additional step and the shank portions of said hooks and functioning to automatically turn the hooks to a folded position in response to the folding of the ladder and to an unfolded position in response to the unfolding of the ladder.

4. A ladder as set forth in claim 3, in which the hook operating means comprises tubular members secured to and projecting below the lower ends of the shank portions of the hooks, each of

said tubular members being provided below the associated hook shank with an opening piercing the wall of said tubular member and communicating with flanking recesses lying at right angles to each other, hook operating pins carried by said additional step and extending into the front uprights through arcuate slots which are formed in the walls of said uprights and are curved about a center coinciding with the axis of the pivotal connections provided between said additional step and the front uprights, said pins extending into the tubular members of the hooks through the openings of said members.
